UNITED STATES PATENT OFFICE.

FRANK R. ASHLEY, OF DENVER, COLORADO.

INTERIOR AWNING CONTROL.

Application filed September 11, 1922. Serial No. 587,316.

To all whom it may concern:

Be it known that I, FRANK R. ASHLEY, a citizen of the United States, and a resident of Denver, Denver County, State of Colorado,

5 have invented an Improvement in Interior Awning Controls, of which the following description, in connection with the accompanying drawings, is a specification, like letters on the drawings representing like

10 parts.

My present invention relates to awning operating devices, and more particularly to awning operating devices capable of operating awnings located on the outside of a 15 building or other structure from the inside of such building or other structure.

Heretofore it has been customary in operating awnings for the operating mechanism to be located on the outside of a building, or other structure, and such construction is objectionable in that it is capable of being tampered with by irresponsible persons, resulting in damage to the awnings and danger to pedestrians as well as those persons tampering with them. Where it has 20 been attempted to operate the awnings from the interior of a building, it has been customary to do so by mechanism that includes complicated gearing as well as projecting 25 operating mechanism such as cranks, levers, or the like, and this mechanism, particularly in the case of heavy awnings, such as, for example, awnings for store doors, windows, and the like, is necessarily so located as to 30 be liable to interference with unauthorized persons, such as patrons of a store, and while not necessarily causing injuries to such persons, the apparel of such persons is liable to be torn or splotched with grease to the 35 annoyance of the operator as well as the patrons.

In my improved invention I have endeavored to overcome defects existing in prior apparatus, and to this end have devised 40 an operating mechanism for awnings by means of which awnings located on the outside of a building may be operated by my improved mechanism located on the interior of such building, and the awning, either in its folded or open position, is securely locked against interference by unauthorized persons and the mechanism employed in such structure is of a character that will not be interfered with or cause 45 injury or annoyance to any person.

The principal object of my invention,

therefore, is an improved mechanism for operating awnings located on the outside of buildings by mechanism operated from the interior of the building.

60

Another object of my invention is an improved locking means for locking the awning operating means, and, therefore, the awning, in any desired position.

Other objects and novel features of the 65 construction and arrangement of parts will appear as the description of the invention progresses.

In the accompanying drawings illustrating 70 preferred embodiments of my invention,

Fig. 1 is a side elevation of an awning showing the operating mechanism controlled from the interior of a building, the wall of which is shown in sectional elevation;

Fig. 2 is a vertical sectional view on the 75 line 2—2 of Fig. 1;

Fig. 3 is a sectional end elevation on the line 3—3 of Fig. 2;

Fig. 4 is an end view of Fig. 2;

Fig. 5 is an end elevation of a portion of 80 the operating handle employed;

Fig. 6 is a vertical sectional view on the line 6—6 of Fig. 1.

Referring to the drawings, 10 designates a wall of a building or other structure, on 85 the outside of which is secured bearing blocks 11, but one of which is shown, to which bearing blocks is pivotally mounted a frame 12 to the outer end or reach of which is secured the lower end of an awning 13, 90 the upper end of this awning 13 being secured to the wall 10 at a point or line beneath a water ledge 14, and to the lower end of this awning 13 is sewed the usual awning fringe 15. Secured to the outer end of the 95 frame 12 by collar 16 is one end of an operating rope or cord 17 which passes through a pulley 18 secured to the wall 10, this rope or cord 17 then passing downwardly and having its end secured in any suitable manner 100 to a pulley 19, this pulley being secured by pin 20 to a shaft 21, which shaft is rotatably mounted in flanged collars 22 and 23 secured respectively to the outside and inside surface of the wall 10 by a plurality of screws 24. 105 The interior of the flanges 22 and 23 are provided with threaded portions 25 and 26 respectively, which receive the internally threaded ends of a sleeve 27, this sleeve 27 being of a diameter to easily slip through an 110 opening or perforation 28 in the wall 10. Rotatably mounted on the outer end of the

shaft 21 and encircling the pulley 19 is a wire frame 29 having an eye formed at its upper end through which passes the operating cord or rope 17. Secured to the shaft 21 by pins 29 are collars 30 which abut against the ends of the portions 25 and 26 of the flanges 22 and 23 respectively, and prevent longitudinal movement of such shaft in the flanges. The end of the shaft 21 on the interior of the wall 10 is milled at 31 to receive the non-circular end of a crank 32, and diametrically arranged on this inner end of the shaft for pivotal movement therein are locking members 33. A spring 34 located in a passage 35 in the end of the shaft 21 and within the confines of the flange 23 tends to force the free ends of such locking members 33, as clearly shown in Figs. 2 and 3. The interior of the flange 23 is provided with a plurality of radially arranged longitudinal slots 35 of sufficient width to allow sliding movement therein of the locking members 33, whereby the shaft 21, and therefore the pulley 19, carried thereby, may be locked in any position in their rotation with respect to the flanges 22 and 23.

The operation of this embodiment of my invention is as follows, it being assumed that the apparatus is assembled as above described and as shown in Figs. 1, 2, 3, 4, and 5. Assuming that the awning is in the position shown in Fig. 1 and that it is desired to move the same from such position to a closed position; that is, with the awning proper 13 folded up and with the frame 12 in a position substantially parallel with the wall 10, the crank 32 is forced onto the end of the shaft on the interior of the wall 10, this crank in its movement compressing the free ends of the locking members 33 against the tension of the spring 34 until, when the crank 32 is fully positioned on the interior of the end of said shaft, said locking members are fully withdrawn from the slots 33 with which they were in engagement thereby allowing the operator to rotate the shaft 21 in the proper direction to wind up the rope or cord 17 onto the pulley 19 and move the outer or free end of the frame 12 up into such position that the frame 12 will lie substantially parallel with the plate 10. When in the desired position, the operator with-

draws the crank 32 from the inner end of the shaft 21, this movement allowing the spring 34 to expand and move the inner or free ends of the locking members 33 into engagement with diametrically opposite grooves or slots 35.

It will be noted that, by reference to Figs. 1 and 6, a hollow member 36 is secured to the frame 12 at a point intermediate its ends, this member being provided with a longitudinal slot 37 to receive a pin 38 secured to, and extending outwardly from, the lower end of a buffering member 39 that is slidably mounted in the member 36, and between the lower end of this member 39 and the bottom of the member 36 is a coil spring 40 which tends to force the member 39 outward from the said member 36. As the frame 12 is moved into a position substantially parallel with the wall 10, as above described, the member 39, engaging with the wall 10, compresses the spring 40. This device is to insure that, when it is desired to lower the awning from the position into which it was folded to that shown in Fig. 1, a preliminary outward swinging movement of the frame 12 will take place simultaneously with the rotation of the shaft 21.

My invention is further described and defined in the form of a claim as follows:

An improved mechanism for operating an awning from the interior of a building comprising a pair of flanges spaced apart from each other, a plurality of locking notches on one of said flanges, a shaft rotatably mounted in said flanges, a plurality of locking fingers pivotally mounted on one end of said shaft and cooperating with the locking notches to maintain the shaft in any desired position with respect to said flanges, means for forcing the free ends of said pivotally mounted locking fingers into engagement with the locking notches, means for forcing the fingers out of said notches to allow rotation of the shaft in the flanges, and a drum secured to the other end of said shaft for associating said operating mechanism with an awning.

In testimony whereof, I have signed my name to this specification.

FRANK R. ASHLEY.
